UNITED STATES PATENT OFFICE.

FRANK M. MARCY, OF WORCESTER, MASSACHUSETTS.

ELECTRIC BOND FOR RAILS.

No. 875,198.

Specification of Letters Patent. Patented Dec. 31, 1907.

Application filed May 3, 1906. Serial No. 314,971

To all whom it may concern:

Be it known that I, FRANK M. MARCY, a citizen of the United States, residing in Worcester, county of Worcester, and State 5 of Massachusetts, have invented an Improvement in Electric Bonds for Rails, of which the following description, in connection with the accompanying drawing, is a specification, like letters on the drawings 10 representing like parts.

This invention has for its object the production of a novel electric bond, in which the copper conductor once embraced by the holder cannot thereafter be rotated to withdraw 15 the conductor from the holder. The end of the conductor is provided with a series of projections and spaces, preferably in the form of screw threads, and the interior of the holder is also shown as provided with 20 projections and spaces, preferably screw threads, so that the spaces and projections of the conductor co-acting with the spaces and projections of the holder will effect a close fit and this fit once made, the conductor 25 and holder are thrown out of round, so that thereafter the conductor cannot be rotated in and withdrawn from the holder. The fit between the conductor and holder is such as to exclude water or moisture.

Figure 1 in side elevation shows the ends 30 of two rails connected in accordance with my invention. Fig. 2 is a section in line x , Fig. 1. Fig. 3 is a section of a rail showing the holder standing in the rail. Fig. 4 is a 35 similar view with the holder supposed to be driven into the rail and the holder and conductor being thrown out of round by a blow or pressure to thus provide an irregular surface in cross section, to prevent any rotation 40 of the conductor in the hole, and Fig. 5 is a section in line x' , showing the threaded ends of the conductor screwed into the hole or pocket in the holder; and Fig. 6 is a modification to be described.

In the drawings, A, B represent parts of 45 the railroad rails that are to be connected by my novel electric bond, the same comprising two holders C and a conductor D. The conductor is a piece of copper of any length, 50 shape, or size in cross section, it being shown in Figs. 1 and 5 as round and as having its ends provided with spaces and projections, preferably screw threads, as at d. The holders comprise heads c having tapered shanks 55 c' and each head is represented as provided with a hole or pocket c² represented as ex-

tended but partially therethrough; said holes or pockets being represented as having spaces and projections in the form of screw threads to be engaged by the ends of the conductor. 60

On referring to Figs. 3 and 5, it will be seen that the hole or pocket c² extends substantially parallel to the end of the head c and that said head is provided with the projecting portion 3, and also that the pocket is situated comparatively close to the outer surface of the projecting portion 3 so that the wall 2 of said hole or pocket is comparatively thin. 70

The projecting portion 3 of the head constitutes what I term a "blow-receiving portion" because in driving the tapered shank c³ of the holder into the holes of the rails formed for them a hammer or sledge is generally used and the blows thereof will be received by the portion 3. The force of the blows of the hammer or sledge flattens the blow-receiving portion 3, as shown in Fig. 4, and in doing so the sectional contour of both 80 the pocket and the conductor is thrown out of round, said conductor and side of the pocket being flattened. When the conductor is screw-threaded as above described and is screw-threaded into the holder, this flattening of the side of the pocket and holder locks the conductor in the holder so that it cannot be turned to unscrew it from the holder. 85

Preferably the hole or pocket in the holder 90 will extend but partially therethrough, so that under no conditions can moisture or water meet the end of the conductor in the holder, although my invention is not limited in all instances to having the hole or pocket 95 extend but partially through the holder.

Uniting the conductor and holder as described results in such intimate union of the ends of the conductor with the holders, that moisture cannot enter the joint, nor, 100 which is of the greatest importance, can the conductor once united with the holder, be extricated by rotating the conductor in the holder.

While I prefer, for convenience, that the 105 spaces and projections of the conductor and the holder shall be made by forming screw threads on the conductor and in the hole or pocket of the holder, yet this invention is not limited to the particular shape of the spaces 110 and projections. These projections resist the withdrawing of the conductor from the

holder by straining longitudinally on the conductor, and this effect would be gained if the projections and spaces were other than screw threads, so long as the projection on one might enter a space of the other and vice versa and thereafter by swaging, or compression, the conductor and holder may be thrown out of round to thus prevent the rotation of the conductor in the holder, and further serve to resist any longitudinal strains on the conductor to withdraw it from the holder. This change of shape of the conductor and holder is one of the essential features of my invention and it will be understood that the holder is a single wire or rod and that the wire or rod is embraced snugly in the holder but the wire and holder are thrown out of round.

In Fig. 6 the conductor, instead of being made in one piece, is made in two pieces, the part f'' being shaped as described with relation to the end of the conductor D , whereas the end pieces f' are connected by means of a flat copper strip f .

Having described my invention, what I claim as new and desire to secure by Letters Patent is:—

1. An electric bond comprising a conductor and two holders each having a hole or pocket to receive the conductor, each pocket presenting a thin wall which is driven in or forced against the conductor by pressure sufficient to flatten the same and secure the conductor in the holder.

2. An electric bond comprising a conductor and a holder therefor provided with a conductor-receiving pocket and presenting a

projecting blow-receiving portion at one side of the pocket whereby when said holder is driven into a rail by a blow delivered on the blow-receiving portion the wall of the pocket is flattened at said side and forced into intimate contact with the conductor.

3. An electric bond comprising a conductor having a series of projections at each end, and holders having corresponding recesses engaging the projections of the conductors, the holder and the conductor near its ends being out of round to restrain a rotation of the conductors in the holder.

4. An electric bond, presenting a holder screw-threaded internally, a conductor threaded externally that the threads of the conductor may engage the threads of the holder, a contacting portion of the holder and conductor being flattened or thrown out of round to prevent the conductor from being rotated in the holder.

5. An electric bond presenting a holder having a hole or pocket extended but partially therethrough, and presenting a thin wall substantially parallel with said hole or pocket, and a conductor in said hole or pocket, a portion of the holder and conductor being thrown out of round to prevent the rotation of the conductor in the hole.

In testimony whereof, I have signed my name to this specification, in the presence of two subscribing witnesses.

FRANK M. MARCY.
